SLIDABLE RACK FOR OVENS AND THE LIKE

Filed Nov. 7, 1938

UNITED STATES PATENT OFFICE

2,225,991

SLIDABLE RACK FOR OVENS AND THE LIKE

Stanley H. Hobson, Rockford, Ill., assignor to
Geo. D. Roper Corporation, Rockford, Ill., a corporation of Illinois

Application November 7, 1938, Serial No. 239,253

2 Claims. (Cl. 211—153)

This invention relates to a slidable shelf or rack for the ovens of gas stoves and electric stoves and cabinet compartments generally, as, for example, refrigerators.

5 I am aware that slidable racks have been formed to provide outwardly extending fingers to engage beneath the rack supporting ledge to support the rack against tilting when slid to an extended position. However, when these racks are 10 made of welded wire construction, the fingers referred to are invariably provided by small pieces of wire welded on, and that sort of construction sooner or later means breakage due to the amount of load imposed upon the fingers when a heavily 15 laden rack is slid to an extreme extended position, exerting considerable leverage upon the fingers. It is therefore the principal object of my invention to provide a rack of welded wire construction in which the fingers are provided 20 by integral extensions on the ends of the rear cross-member of the frame of the rack and wherein the welded connections are subjected to compression instead of tension when the rack is extended and load is imposed upon the fingers, 25 whereby to eliminate danger of breakage of the fingers and provide generally a much stronger and more durable construction.

The invention is illustrated in the accompanying drawing, in which—

30 Fig. 1 is a horizontal section through an oven showing in plan view a slidable rack made in accordance with my invention;

Fig. 2 is a section on the line 2—2 of Fig. 1, showing in the same section a portion of another 35 rack in fully extended position and raised so as to permit withdrawal from the oven;

Fig. 3 is an enlarged sectional detail illustrating the last named rack prior to the raising thereof, as it appears when extended as far as it will 40 go;

Fig. 4 is a sectional detail on the same scale as Fig. 3, but in a transverse plane, and

Fig. 5 is a perspective view of the same rear corner of the rack.

45 The same reference numerals are applied to corresponding parts throughout the views.

In Figs. 1 and 2, the numeral 6 designates the oven of a gas range in which are provided horizontal ledges 7 on the opposite sides thereof in 50 vertically spaced parallel relation for the support of slidable racks indicated generally by the numeral 8. It is desired to have these racks supported against tilting when pulled out to an extended position so that the housewife can inspect 55 the food being prepared in the oven; without hav-

ing to remove utensils, and so that there will be no danger of burning the hands and dropping or spilling anything. Slidable racks also facilitate the placing of articles in the oven so that the oven can be used to its full capacity without difficulty. 5 It is also desired to have the racks quickly and easily removable so that they may be placed at different elevations in the oven and can be readily cleaned, and it is also desired to definitely limit the outward sliding movement of the racks so 10 that there will be no danger of accidentally withdrawing a rack off its supporting ledges. The stop projections 9 on the bottoms of the ledges 7 come into abutment with fingers 10 on the racks for the latter purpose, the fingers moving along 15 the under side of the ledges both to provide support against tilting when the racks are extended and to serve as stops to limit outward movement. Generally speaking, it is old to provide outwardly extending fingers for the purpose stated and to 20 have the same located in rearwardly spaced relation to the rear edges 11 of the rack on which the rack fulcrums when raised, as shown in Fig. 2, whereby to permit the fingers 10 to pass under the stop projections 9 so that the rack can be 25 removed and replaced without interference with the stop projections. As above indicated, this invention while illustrated as applied to a gas 30 stove may be used in electric stoves also, and, in fact, in any compartments wherever slidable shelves are used, as, for example, in refrigerators.

The racks, in accordance with my invention, are of welded wire construction, each comprising a wire frame 12 of heavier wire with lighter wires 13 disposed transversely with respect thereto and welded in place at the ends and also at the middle where a cross-member 14 is provided to lend stiffness and rigidity. The wire frame 12 is made up from a substantially U-shaped piece 15 providing a cross-portion 16 at one end of the rack and side portions 17 and 18 along opposite sides thereof, the latter having inwardly bent end portions 19 and 20 projecting under the side-most cross-wires 13 and welded thereto, as indicated at 21. The frame is completed by a rear cross-member 22 of wire preferably of the same gauge as the U-shaped frame member 15 and spanning the tops of the rearwardly projecting end portions 23 of the sidemost cross-wires 13 and welded thereto, as indicated at 24. The opposite ends of the cross-member 22 are bent downwardly, as at 25, and laterally, as at 26, to provide the fingers 10 on the end portions of the cross-member 22.

With this construction, it is clear that since 55

the fingers 10 are formed integral with the rear cross-member 22 of the frame, there is no danger of the fingers being pulled off in the event the rack happens to be unusually heavily loaded and is slid to an extreme extended position where it exerts the greatest leverage upon the fingers. Furthermore, it is obvious that when the fingers 10 are placed under load, there is a downward pull on the ends of the cross-member 22 and a corresponding upward thrust on the bent end portions 19 of the main frame member 15, thereby placing the welded joints 21 and 24 under compression instead of tension, so that there is no danger whatever of any of the wires tearing loose.

It is believed the foregoing description conveys a good understanding of the objects and advantages of my invention. The appended claims have been drawn with a view to covering all legitimate modifications and adaptations.

I claim:

1. As an article of manufacture, a rack comprising a frame having a front member and spaced side members with transverse end portions projecting inwardly at the rear toward each other, and an end member in rigid relation to the frame and in transverse relation to said side members and disposed adjacent said end portions, and cross-pieces on said frame substantially parallel to the frame side members, the rear end portions of said cross-pieces extending crosswise relative to the transverse end portions of said side members and certain of said cross-

pieces being secured on top thereof, said end member having the rear extremities of the cross-pieces disposed under and in transverse relation to the same, the extremities of said end member being formed to provide integral downwardly and outwardly projecting fingers below the plane of the end portions of said side members, and the front end portions of said cross-pieces being supported by said front member.

2. As an article of manufacture, a rack comprising a U-shaped frame member the cross-portion of which forms the front member of the frame and the arms of which form the side members of the frame, said side members having the rear end portions thereof bent inwardly toward one another, cross-members extending from front to rear of the frame, all being secured at their front ends in transverse relation to the front member of the frame and some of said members extending over the inwardly bent end portions of the side members and being secured thereto, and a rear frame member in rigid relation to the U-shaped frame member and superimposed on the rear ends of the cross-members in transverse relation thereto, the opposite end portions of said rear frame member being disposed adjacent the inwardly bent end portions of the side members and having the ends thereof bent downwardly and outwardly to provide fingers in a plane below and spaced relative to the side members.

STANLEY H. HOBSON.
